CONDIMENT SET

Milton Immermann, Piermont, and Robert H. Ensign,
Bronxville, N. Y., assignors to International Minerals
& Chemical Corporation, a corporation of New York

Application June 27, 1955, Serial No. 36,699

Term of patent 14 years

(Cl. D44—22)

We claim:

The ornamental design for condiment set, substantially as shown.
